HAROLD F. ELLIOTT, OF PALO ALTO, CALIFORNIA, ASSIGNOR, BY MESNE ASSIGNMENTS,
TO RADIO CORPORATION OF AMERICA, OF NEW YORK, N. Y., A CORPORATION OF
DELAWARE

RADIO RECEIVING SYSTEM

Application filed December 22, 1925. Serial No. 77,039.

This invention relates to the reception and amplification of weak electrical impulses, such for example as those produced by radio signals.

5 It is one of the objects of my invention to make it possible to cover a broad range of frequencies of electrical energy that carries the signals to be observed, by a single receiver system, and in such manner that but a single 55 tuning adjustment is needed. This kind of system is useful not only to enable a comparatively unskilled amateur operator to use his set in the most satisfactory manner, but also to enable a skilled commercial operator to 60 10 cover his range so that he may obtain the signals he is to receive to the substantial exclusion of all others, and merely by the aid of simple manipulation.

It is another object of my invention to make 20 it possible to accomplish these results by the aid of inexpensive apparatus, requiring no intricate adjustments either in the process of manufacture or in operation. In fact, I arrange the receiving system in such a way that 25 it is necessary to tune only a single circuit, by the aid of a variable element, which need have but a comparatively small range of adjustment to take care of a very broad range in the frequencies of the signals to be received.

30 I am enabled to secure these highly beneficial results by combining the signals received with locally generated radio frequency energy, having a frequency that is substantially higher than the highest frequency to 35 be received whereby the signals from then on are carried by these much higher frequency currents. Since it is possible so to arrange the system that this higher frequency is substantially constant for all signals received, the

40 subsequent detection and amplification can be arranged once and for all; and the single tuning function of adjusting this frequency is all that is required to set the system into proper receptive condition. Of course for 45 selectivity it is usually desirable to provide a filter, and one or two additional amplifiers operating at successively lower frequencies.

By the aid of my invention, it is entirely 50 feasible to detect and amplify signals carried by electrical energy of frequency between 100

kilocycles (3000 meters) to 2,000 kilocycles (150 meters). Such a broad field renders it possible to allocate the frequencies among the various transmitting stations in a way 55 that will ensure against appreciable interference, and to provide many more such stations.

My invention possesses many other advantages, and has other objects which may be made more easily apparent from a consideration of several embodiments of my invention. For this purpose I have shown a form 60 in the drawing accompanying and forming part of the present specification. I shall now proceed to describe this form in detail, which 65 illustrates the general principles of my invention; but it is to be understood that this detailed description is not to be taken in a limiting sense, since the scope of my invention is best defined by the appended claims.

Figure 1 is a wiring diagram of one embodiment of my invention; and

Figure 2 is a diagram of a modification.

For the purpose of presenting a concrete example of my invention, I shall assume that the receiving systems illustrated are arranged to receive signals carried by radiations of between 100 kilocycles and 2,000 kilocycles. Furthermore, in Fig. 1 I illustrate a scheme whereby the final translating device, such as a loud speaker 11, and 75 its connections are used also for forming an energy absorbing circuit, as disclosed and claimed in my Patent No. 1,737,078 granted November 26, 1929, and entitled: Radio receiving system. In that scheme, the leads 80 12 connecting the speaker 11 to the output terminals 13 of the last series of amplifiers 14, include coils 15 and 65, both of which serve as primaries of a transformer 16. This 85 transformer serves to pass the received energy to further elements of the system, as will be hereinafter described; the metallic parts of the loud speaker 11 cooperate with the earth, or other separated metallic elements of the system, to form an open 90 absorbing circuit. In the present instance, one of the output terminals 13 is grounded at 17, in order to provide a counterpoise for the loudspeaker. Since the theory of operation of such an absorbing circuit is ade- 95 100

quately described in my prior application heretofore identified, it is not essential to enter into further details with regard thereto.

5 The output coil 18 of transformer 16 preferably connects to a filter 19 that is arranged to cut off all energy above the range of the set; in this instance, the filter is to cut off all energy of over 2,000 kilocycles. The cut-
10 put of the filter 19 connects to an impedance 20, shown in this instance as a resistance, whereby by appropriate adjustment, the strength of the signals can be varied. It is furthermore to be noted that the absorbing circuit is aperiodic, eliminating one adjustment, which is now quite common.

15 The potential differences existing across the resistance 20 are utilized to affect succeeding elements in such manner that the signal is transferred to a carrier wave of certain definite frequency value which is much higher than that of any signal to be received. For example, the arrangement is such that the carrier wave becomes 2,500 kilocycles. This result can readily be effected by providing a source of oscillations, the frequency of which is adjustable, and which combines with the original carrier wave to produce the desired frequency. Subsequently, the new carrier wave must be passed through a detector in order to separate it from the original carrier.

20 In the present instance, an audion 21 is shown as serving the double purpose of detector and oscillator. Since it is well-known how such a result can be obtained, it is sufficient merely to point out that the input and output circuits of the audion are coupled as by coils 22 and 23, whereby the oscillatory function can be secured, and that the system includes the usual A battery 24, B battery 25, and the C battery 26. The input circuit also includes a variable impedance, such as condenser 27, bridging in this instance, coil 23, whereby a tunable circuit is produced. By varying condenser 27, the frequency of oscillations can be correspondingly varied. The output circuit includes a tuned circuit formed by a primary coil 28, and a condenser 29, which is sharply tuned to the frequency of the new carrier wave—2,500 kilocycles—and which thus acts as a filter to prevent materially variant frequencies from affecting substantially the secondary 30.

25 Before proceeding with the description further, it is advisable to consider the operation of the system so far set forth.

The system is so designed that it operates over a broad frequency range, as stated heretofore; between 100 kilocycles and 2,000 kilocycles. Thus the highest frequency is twenty times larger than the lowest. Such a large range it has been heretofore difficult if not impossible to secure by a simple receiving set, due to the difficulty in obtaining variable

tuning elements and circuits that could efficiently render the system selective. With the use of a higher frequency source, such as audion 21, it is possible to transform the frequency no matter what it may be within that range, to 2,500 kilocycles even when the oscillator has but a relatively small frequency range. Thus all the variation required is from 2,600 kilocycles to 4,500 kilocycles, so that the difference frequency can always be 2,500 kilocycles. This range is less than a 2:1 variation, and can easily be secured by conventional tuning elements, such as the variable condenser 27.

These secondary 30 is bridged by a condenser 31, which with this secondary, forms a circuit accurately tuned to 2,500 kilocycles, whereby interfering signals can be attenuated to a large extent. Rectangle 32 represents an amplifier and filter tuned to 2500 kilocycles.

30 The output of this element is shown in this instance as connected to a second detector and oscillator 33 which operates on a frequency that combines with 2500 kilocycles to produce a much lower carrier wave, say of 400 kilocycles. In some cases, this second detector-oscillator can be omitted, and instead, audio frequency amplification, subsequent to detection, can be used. In this instance, the detector-oscillator generates 2100 kilocycle current to perform its function; and this element in fact, can comprise two devices, one an oscillator and the other a detector, connected in a well-known manner. The resultant 400 kilocycle current carrying the signal is passed to an appropriate filter and amplifier 34, then to a detector 35, and finally, to the audio frequency amplifier 14. Thence, the detected signal is passed to the translating device 11, as heretofore described.

35 In some instances, in order to secure still greater selectivity, it is advisable to step down the carrier frequency still further, say to about 50 kilocycles, before final detection and amplification. Such a scheme is shown, merely diagrammatically, in Fig. 2. In this figure, an aperiodic antenna circuit 36 is shown as coupled to a low pass filter 55 passing energy only at and below 2,000 kilocycles, as before, in the adjustable oscillator-detector unit 56. A 2500 kilocycle filter and amplifier 57 succeeds this unit, and passes its energy to a fixed oscillator-detector unit 58 having an output of 400 kilocycles. From this unit the energy is passed to a 400 kilocycle filter and amplifier 59, thence to a third oscillator-detector unit 60 that has a 50 kilocycle output. This output may be filtered and amplified by the amplifier unit 61, detected in detector 62 and amplified at audio frequency by amplifier 63. A translating device 64, such as a loud speaker, makes the signal perceptible.

40 A concrete example of signal reception with my system serves to show that this

scheme is rendered substantially clear of interference, even when signals are picked up differing by as little as 15 kilocycles. Let it be assumed that a signal of 1000 kilocycles is to be received, while at the same time, a signal of 1015 kilocycles also affects the absorbing circuit. Both these signals will of course pass filter 19 or 55. The adjustable oscillator-detector unit 21 or 56 is adjusted to provide oscillations of 3,500 kilocycles, reacting with the 1000 kilocycle signal to give 2,500 kilocycles. The interfering signal would still be present at 2485 kilocycles. The filter 30 or 57, although tuned to 2500 kilocycles, may still not discriminate sharply between the two signals, since it must pass a band of about 7.5 kilocycles above and below each carrier wave in order to obtain good quality in speech and music. However, the second oscillator-detector unit 33 or 58 steps the desired signal frequency down to 400, and the interfering signal to 385. These two frequencies can be more easily differentiated in the 400 kilocycle detector and amplifier 34 or 59. Of course it is possible to obtain 400 kilocycle current in the output of detector-oscillator 33 or 58 by providing it with current of 1,700 kilocycles, but such a current cannot reach this unit due to the sharply tuned 2,500 kilocycle filter 32 or 57. The differentiation can be carried still further by the addition of a 350 kilocycle oscillator and detector 60, giving a 50 kilocycle output for the desired signal and 35 kilocycle for the interfering signal; these signals can very readily be differentiated. Any current neighboring 300 kilocycles that would react to give a 50 kilocycle output for the unit 60, is efficiently prevented from doing so by the 400 kilocycle filter and amplifier 59.

This system of fixed filter and amplifier circuits, arranged in cascade, may be made to give any desired degree of selectivity. The first filter 30 or 57 is required to discriminate only between signals of 1,700 and 2,500 kilocycles; the second filter 34 or 59, between signals of 300 and 400 kilocycles; and the third filter 61, between 35 and 50 kilocycles, in order that the discrimination as a whole may be 15 kilocycles. This makes it feasible to do away with tuning the input circuit to the receiver, and to employ but a single adjustable circuit, the first oscillator, to produce a current which when mingled with the desired signal, will give 2,500 kilocycles, or whatever other value it is desired that the first filter system should have.

Generally it may be stated that if the first filter is tuned to n cycles, and the succeeding filter to n_1 , then the first filter must eliminate energy in the neighborhood of $n-2n_1$ cycles in order to prevent the intermediate oscillator from combining with interfering energy to produce an undesired signal of n_1 cycles. Resonant circuits can readily be designed to

have this desired degree of discrimination. Furthermore, as heretofore pointed out, only a small range of variation is required for the first oscillator to provide a broad range reception.

The condenser 27 of the first oscillator can obviously be made to vary the frequency or wave length in any desired fashion. If a straight line frequency law is followed, and all broadcast stations between 100 and 2,000 kilocycles are separated by 15 kilocycles, then all stations would be evenly spaced over this range, and over 125 separate stations may be accommodated in a given region. Since some of the stations would have limited sending radii, it is likely that several times this number can be operated simultaneously within the United States, Canada, and Mexico without material interference, and a like number in Europe. It would also be possible for a few very high power stations to use the relatively long waves from 2,000 to 3,000 meters (100 to 150 kilocycles) without employing special receiving apparatus to detect their signals. Although several European stations now operate in this range, they cannot be received in this country without unusual or special equipment.

I claim:

1. In a receiving system, a local oscillator of adjustable frequency arranged to heterodyne with the received signals to produce a constant frequency much higher than any to be received, a fixed filter for passing a narrow band neighboring said constant frequency, a fixed oscillator for reducing the said frequency by heterodyning to a much lower constant value, and a filter passing a narrow band neighboring said lower frequency.

2. The method of receiving and selecting signals of wide frequency range, which comprises first increasing the frequency of the signal to a definite, constant value, and then successively operating upon the said higher frequency to reduce it to set, low values in order to impart selectivity to the system.

3. In a receiving system, adjustable means for operating upon incoming signaling impulses to increase the frequency of the carrier current, to a definite, set value, and non-adjustable means successively operating upon the said increased frequency to reduce it in steps to set, low values in order to impart selectivity to the system.

4. The method of selectively receiving high frequency signals, which comprises shifting the carrier frequency of the signals to a constant value higher than the highest frequency to be received, and subsequently reducing the carrier frequency to a lower value.

5. The method as set forth in claim 4, with the addition of the step of filtering the

higher frequency pulsations before the frequency is reduced.

6. The method of receiving any of high frequency signals that fall within a definite frequency range, by the aid of tunable frequency shifting apparatus, which comprises adjusting the tunable apparatus to cause the shift in frequency to a constant value for any of the signals, said value being materially higher than the upper limit of the range of reception, whereby the tunable apparatus need be adjusted through a relatively small range to obtain the constant frequency for any signals within the said definite frequency range.

7. The method of selectively receiving high frequency signals within a definite frequency range, which comprises picking up the signal impulses, next filtering the signal impulses so as to include only signals within said range, and raising the frequency of the desired signal to a definite constant value.

8. The method of selectively receiving high frequency signals within a definite frequency range, which comprises picking up the signal impulses, next filtering the signal impulses so as to include only signals within said range, raising the frequency of the desired signal to a definite constant value, filtering the raised frequency signals to exclude all except the constant frequency, and lastly lowering the frequency.

9. In a receiving system for high frequency signals, means for increasing the carrier frequency of the signals to a constant value higher than the highest frequency to be received, and means for subsequently reducing the frequency to a lower fixed value.

40 10. In a receiving system for high frequency signals, means for increasing the carrier frequency of the signals to a constant value higher than the highest frequency to be received, permanently adjusted means for filtering said higher frequency to exclude all but said higher frequency signal carrier, and means for subsequently reducing the frequency to a lower fixed value.

50 11. The combination as set forth in claim 10, in which the means for reducing the frequency is permanently adjusted.

55 12. In a receiving system for high frequency signals that fall within a definite frequency range, means for picking up the signal impulses, means for excluding all signals outside the range, and means for raising the carrier frequency of the desired signal to a definite constant value.

60 13. In a receiving system for high frequency signals that fall within a definite frequency range, means for picking up the signal impulses, means for excluding all signals outside the range, means for raising the carrier frequency of the desired signal to a definite constant value, permanently adjust-

ed means for filtering said higher frequency to exclude all but said higher frequency signal carrier, and means for subsequently reducing the said higher frequency to a lower fixed value.

70 14. In a heterodyne receiver, the combination with a radio frequency circuit for the reception of a certain range of signal frequencies, of means for producing local oscillation frequencies and a beat frequency therefrom, which beat frequency added to said range of oscillation frequencies provides a range of image frequencies relatively widely separated from and corresponding to said range of signal frequencies.

80 15. The method for the heterodyne reception of radio signals which comprises selecting a range of frequencies to be received, applying a range of frequencies thereto to produce a constant beat frequency therefrom throughout said range, said beat frequency and said range of oscillation frequencies being such that an image frequency range is produced thereby which is relatively widely separated from the range of signal frequency to be received.

90 In witness whereof I have hereunto set my hand.

HAROLD F. ELLIOTT.
